EDUCATIONAL DEVICE OR THE LIKE

Robert Paul Benz, 410 Ivywood Drive,
Oxnard, Calif. 93030

Filed Oct. 14, 1968, Ser. No. 13,988

Term of patent 14 years

Int. Cl. D19—08

U.S. Cl. D25—1

FIG. 1

FIG. 2

FIG. 4

FIG. 3

FIG. 5

FIGURE 1 is a perspective view of an educational device or the like showing my new design;

I claim:

The ornamental design for an educational device or the like, substantially as shown.
